UNITED STATES PATENT OFFICE.

WILLIAM J. HOLWAY, OF MANSFIELD, OHIO, ASSIGNOR OF TWO-THIRDS TO J. H. MCGINTY, OF SAME PLACE, AND ROBERT LOWE, OF WASHINGTON, PENNSYLVANIA.

SOLDERING-IRON.

SPECIFICATION forming part of Letters Patent No. 673,775, dated May 7, 1901.

Application filed June 23, 1900. Serial No. 21,359. (No model.)

To all whom it may concern:

Be it known that I, WILLIAM J. HOLWAY, a citizen of the United States, residing at Mansfield, in the county of Richland and State of Ohio, have invented a new and useful Soldering-Iron, of which the following is a specification.

The invention relates to improvements in self-heating soldering-irons.

10 The object of the present invention is to improve the construction of self-heating soldering-irons and to provide a simple and comparatively inexpensive one adapted to employ a solid copper head or soldering-tip and 15 capable of heating the inner end of the same and of directing the flame into a cylindrical form and of concentrating it against the copper head or soldering-tip, whereby the latter will be practically enveloped in a thin sheet 20 of flame throughout the major portion of its length.

The invention consists in the construction and novel combination and arrangement of parts hereinafter fully described, illustrated 25 in the accompanying drawings, and pointed out in the claims hereto appended.

In the drawings, Figure 1 is a side elevation of a soldering-iron constructed in accordance with this invention. Fig. 2 is a longitudinal 30 sectional view of the same. Fig. 3 is a transverse sectional view on line 3 3 of Fig. 2. Fig. 4 is a similar view on line 4 4. Fig. 5 is a detail perspective view of the inner conical sleeve of the flame-concentrating device.

35 Like numerals of reference designate corresponding parts in all the figures of the drawings.

1 designates a reservoir designed to contain gasolene or other suitable liquid-hydro- 40 carbon fuel and arranged at the inner end of a hollow handle 2 and provided with a suitable filling-opening 3 and cap 4, located at one side, as clearly shown in Fig. 1 of the accompanying drawings. The reservoir may be 45 constructed in any suitable manner, and it communicates with a tube or pipe 5, which extends through the hollow handle 2, and the latter, which is preferably constructed of wood, may have a lining of asbestos or other

suitable material interposed between it and 50 the tube or pipe 5.

The outer end of the tube or pipe 5 is coupled to the inner end of an approximately cylindrical body 6, composed of a cylindrical inner portion 7 and an outer annular portion 8, connected with the inner cylindrical portion by arms 9, 10, and 11. The arms 9 are solid, and the arms 10 and 11 are provided with passages, the passage of the arm 10 being in communication with the pipe or tube 5 60 and being adapted to convey the liquid hydrocarbon to an annular generating-chamber 12, located within the outer annular portion 8 of the body, at the outer end thereof. The passage 11, which is located at the opposite side 65 of the body from the passage of the arm 10, extends from the annular gas-generating chamber to a transverse passage 13, located at the inner cylindrical portion of the body and communicating with a centrally-arranged 70 burner 14, extending outward from the inner cylindrical portion 7, as clearly illustrated in Fig. 2 of the accompanying drawings. The inner portion of the outer annular part of the body is provided with an annular series of 75 apertures 15, which are adapted to admit air into the space or chamber 16, and the bottom or inner wall 17 of the chamber 16 is provided with a central opening and has an annular flange or wall 18 extending inward from the 80 same and projecting into the space within the annular portion 8. By this construction air is admitted into the cylindrical body to support the combustion, and the discharge of the vapor is controlled by a needle-valve 19, hav- 85

ing a stem extending through the tube 5 and the reservoir 1 and provided at its rear end with a handle 20. In order to retard the flow of the gasolene or other liquid fuel and render the same uniform, a spirally-coiled wire 90 22 is arranged within the inner cylindrical portion of the body and is disposed around the central valve-socket 7^a, through which the valve-stem 21 is adapted to move.

The flame from the burner is concentrated 95 and caused to envelop a copper soldering head or tip 24 by a device consisting of inner and outer conical sleeves 25 and 26, which

are slightly tapered, as clearly shown in Fig. 2. The inner tapered sleeve 25 is provided with inner and outer interior screw-threads 27 and 28, adapted to engage, respectively, a threaded annular flange 29 of the body and a reduced shank 30 of the soldering-tip, whereby the latter is connected with the body. The annular flange 29 of the body is arranged around the opening at the outer end thereof and has a concave inner face, and the shank 30, which is threaded adjacent to the shoulder formed by the reduction of the tip, is extended inward beyond the screw-threads and projects into the inner tapering sleeve, practically to the inner end thereof, whereby the solid inner end or shank of the soldering-tip will be heated by the flame of the burner before it is spread by the concentrating device and directed by the same upon the outer portion of the soldering-tip. The inner end of the inner tapered sleeve is provided with exterior screw-threads 31, located adjacent to an annular flange 32 and adapted to receive and be engaged by interior screw-threads 33 of the outer tapered sleeve 26. The outer portion of the inner tapering sleeve is provided with an annular series of longitudinal grooves 34 and an annular series of apertures 35, arranged at the inner ends of the grooves and permitting the flame to enter the narrow annular space between the inner and outer sleeves. The outer sleeve, which is imperforate, extends a considerable distance beyond the inner sleeve and is adapted to concentrate the flame into a thin sheet which envelops the major portion of the solid copper soldering-tip 24, whereby the latter is heated to a maximum degree from a given quantity of liquid-hydrocarbon fuel. The concentrating device directs the flame upon the outer portion of the body of the soldering-tip after the flame has been partially spread by the solid inner end or shank of the said tip, and this contact of the flame with the inner end or shank of the tip increases the heating power of the device and in connection with the concentrating device secures a maximum effect.

In starting the self-heating soldering-iron the outer annular portion of the body is heated by any suitable means until it has attained a sufficient temperature to vaporize the liquid fuel. The vapor may then be ignited, and the device will be self-heating, as will be readily understood.

It will be seen that the soldering-iron is simple and comparatively inexpensive in construction, that the soldering-tip is solid, and that the inner end of the same is subjected to the action of the flame before the latter is concentrated upon the outer portion of the tip. It will also be apparent that the concentrating device will cause the major portion of the soldering-tip to be enveloped in a thin sheet of flame, whereby the tip will be heated to a high degree.

What I claim is—

1. A self-heating soldering-iron comprising

a hollow handle, a reservoir, a body composed of an inner cylindrical portion having an inwardly-extending valve-socket, an outer annular portion having a generating-chamber and spaced from the inner portion and provided at its sides and inner end with openings, arms spaced apart to provide openings and connected with the inner and outer portions, and provided with interior passages, a valve having a stem arranged in the said socket, and a spirally-coiled wire located within the inner cylindrical portion of the body and arranged around the said socket, substantially as described.

2. A self-heating soldering-iron comprising a handle, a reservoir, a body composed of an inner cylindrical portion having a central valve and communicating with the reservoir, the outer annular portion having a generating-chamber and provided with a central longitudinal space located opposite the valve, and arms connecting the inner and outer portions of the body and spaced apart and provided with interior passages communicating with the generating-chamber and with the interior of the inner cylindrical portion, and a tip, substantially as described.

3. In a self-heating soldering-iron, the combination of a body comprising an inner cylindrical portion, an outer annular portion spaced from the inner portion and having a central opening and provided with an annular generating-chamber, means for connecting the inner and outer portions of the body, a solid soldering-tip located at the outer end of the central opening of the outer portion of the body, and a concentrating device connecting the tip with the outer annular portion of the body and composed of inner and outer sleeves, substantially as described.

4. In a self-heating soldering-iron, the combination of a body, having a burner and composed of the inner cylindrical portion and the outer annular portion, spaced from the inner portion and connected therewith, said outer portion having a central opening and provided with a generating-chamber surrounding the same, a soldering-tip arranged at the central opening of the outer portion of the body, and a concentrating device receiving the inner end of the tip and composed of inner and outer sleeves, secured to the annular portion of the body and arranged to direct the flame upon the tip, substantially as and for the purpose described.

5. In a self-heating soldering-iron, the combination of a body having a burner and composed of an inner cylindrical portion, and an outer annular portion spaced from and connected with the inner portion and provided with an annular generating-chamber surrounding its central opening, a soldering-tip having a reduced inner end located at the opening of the outer portion of the body, and a concentrating device composed of an inner sleeve secured to the tip and to the annular portion of the body, and the outer sleeve also

secured to the annular portion of the body and extending outward beyond the inner sleeve, substantially as described.

6. In a self-heating soldering-iron, the combination of a body having a burner and composed of an inner cylindrical portion and an outer annular portion spaced from the inner portion and connected with the same and having a central opening and provided with a generating-chamber extending around the said opening, a soldering-tip, and a concentrating device composed of an inner sleeve secured to the outer annular portion of the

body and to the tip and provided with an annular series of apertures and grooves, and the 15 imperforate outer sleeve secured to the outer annular portion of the body and extending beyond the inner sleeve, substantially as described.

In testimony that I claim the foregoing as 20 my own I have hereto affixed my signature in the presence of two witnesses.

WILLIAM J. HOLWAY.
